UNITED STATES PATENT OFFICE.

GEORGE C. SNYDER, OF NEW YORK, N. Y., ASSIGNOR TO THE THREADLESS BUTTON COMPANY, A CORPORATION OF CONNECTICUT.

SNAP-FASTENER.

1,205,048.

Specification of Letters Patent. Patented Nov. 14, 1916.

Application filed February 2, 1915. Serial No. 5,611.

To all whom it may concern:

Be it known that I, GEORGE C. SNYDER, a citizen of the United States, residing at New York, county of New York, and State 5 of New York, have invented certain new and useful Improvements in Snap-Fasteners, and I do hereby declare the following to be a full, clear, and exact description of the invention, such as will enable others 10 skilled in the art to which it appertains to make and use the same.

This invention relates to fastening devices, and more particularly to snap fasteners of the threadless type.

15 Heretofore threadless snap fasteners, or, in other words, snap fasteners, the socket and stud members of which each comprises elements mechanically locked and attached to the fabric, have been limited in use to 20 gloves, pocket-books, and similar articles, as the parts have never been so constructed as to stand the treatment received in laundrying.

It is the principal object of this invention 25 to provide a snap fastener especially adapted for use on shirts, underwear and other articles which have to be laundried.

In furtherance of this and other objects which will hereinafter appear as the specification proceeds, the invention consists in the 30 novel construction and arrangement of parts hereinafter described.

The invention is illustrated in the accompanying drawings:—Figure 1 of which is 35 a vertical section showing the parts of the socket member of the fastener in position ready to be assembled, together with a portion of the assembling mechanism; Fig. 2 is a plan view of the spring member which 40 is associated with the socket member in the manner hereinafter described; Fig. 3 is a vertical section through the spring member taken on the line 3—3 of Fig. 2; Fig. 4 is a vertical section corresponding to Fig. 1, 45 representing the parts shown in Fig. 1 in the position which they assume at the completion of the down stroke of the plunger of the assembling mechanism; Fig. 5 is a vertical section through the socket member 50 of the fastening device showing the socket member attached to the fabric and the parts thereof completely assembled or “set”; Fig. 6 is a vertical section through the stud member showing the same attached to the fabric;

Fig. 7 is a similar view showing the use of 55 a cap for covering the top of the stud member; Fig. 8 is a vertical section through the entire fastening device showing the socket member applied to the stud member, or otherwise stated, showing the stud member 60 inserted in the socket member; Fig. 9 is an enlarged plan view of the stud member shown in Fig. 6; and Fig. 10 is a perspective view showing one strip of fabric having the stud members applied thereto, and a 65 second strip of fabric having the socket members applied thereto.

Referring to the drawings, and particularly to Figs. 1, 2 and 3, the socket member consists of a head portion 1, which may be 70 of any shape and size desired, as the specific construction of the head of the socket member is immaterial, so far as the present invention is concerned. Associated with the socket member is a tubular shank portion 75 13 which is provided with a basal inturned flange 14. As will hereinafter appear, this flange is adapted to be deflected and turned farther in toward the walls of the shank when the thimble hereinafter referred to is 80 forced into and expanded in the tubular shank 13. A reinforcing collar 2 encircles the tubular shank 13, and is provided with a fabric-clamping flange 15. This portion 85 of the socket member so far described may be supported on a suitable work table 3, of any assembling mechanism, when it is desired to attach the socket member to the fabric. The fabric shown at 8 is then 90 stretched over the opening at the base of the shank, as clearly shown in Fig. 1, and a metallic thimble 4 having substantially the cross section shown in the drawing is then forced into the shank 13 by means of the plunger 7 and the yielding portion 6 carried by the plunger. The thimble 4, as it 95 is forced into the shank 13, carries with it a portion of the fabric 8. When the walls of the thimble pass the edge of the inturned flange 14, a disk is cut from the fabric and is carried down with the thimble to the head of the socket member, as clearly shown at 100 16 in Fig. 4. When the head of the thimble strikes the head 1, the walls of the thimble commence to collapse and expand radially 105 to form a bulbous head thereon, as best shown in Fig. 4.

The part 6 of the plunger is yieldingly

mounted with respect to the part 7, so that after the thimble commences to collapse, a basal flange 17 on the thimble may be forced into clamping engagement with the fabric, 5 the fabric being tightly gripped between the flange 15 on the member 2, and the flange 17 on the thimble. As the thimble is being forced into the shank 13, the fabric and the thimble deflect the flange 14 and bend the 10 same into closer proximity with the walls of the shank 13, as shown in Fig. 4. As the head portion of the thimble expands radially in all directions behind this flange 14, it is obvious that the thimble is firmly interlocked in the 15 shank 13, and the fabric tightly gripped between the gripping flanges of the collar 2 and thimble 4, respectively. This collapsing 20 action of the thimble behind the flange 14 is substantially the same as the collapsing action of the thimbles shown in my co-pending applications, Ser. Nos. 844,434 and 847,938, filed June 11, 1914 and June 29, 1914, respectively. In the present instance, however, the thimble 4 has associated therewith, a spring element 5 having a plurality 25 of depending resilient fingers 18. This spring element 5 is applied to the thimble as shown in Fig. 1, being held in place by means of the peripheral turned-over portion 30 19 of the thimble. The spring element 5 is so positioned with respect to the thimble that the resilient fingers 18 project into the interior of the thimble. When the thimble collapses behind the flange 14, in the manner above described, the extremities of the resilient fingers 18 will be slightly spaced from the walls of the thimble, as clearly 35 shown in Fig. 4.

The attached socket member is shown in 40 Fig. 5, the parts of which are firmly locked to each other and to the fabric.

The stud member may also be mechanically attached to the fabric by the collapsing action of a thimble, as exemplified in Figs. 45 6 and 7. The outer part of the stud member may consist of a tubular cylindraceous element 10, also provided with a basal in-turned flange 14', similar to the flange 14 of the shank 13. In Figs. 6 and 7, however, this flange is shown deflected into close proximity with the walls of the tubular member 10, as the thimble and fabric so deflect the flange during the assembling 50 operation. The thimble is shown at 11, but differs from the thimble 4 used for the socket member, as it is provided with no fabric-clamping flange. This is to prevent any of the metal of the fastener from contacting with the body, but obviously, a flange may 55 be used on the thimble, if so desired. As the fabric-clamping flange is omitted from the thimble, in the form shown in Figs. 6 and 7, the thimble must be so designed as to carry a portion of the fabric 9 into the 60 ring-like member 10 during setting, so that 65

as the thimble expands behind the flange 14', the fabric will be gripped between the walls of the thimble and the walls of the ring-like member 10.

The cylindraceous stud member 10 is provided with a rounded flange 20 for co-operation with the resilient fingers 18, as will hereinafter appear. It will be noted that in the form of the stud member shown in Fig. 6, the head of the stud member is open 70 and a portion of the fabric is visible, as illustrated in Fig. 9, and the stud member will, therefore, present a finished appearance. If so desired, however, a cap or cover 75 12, of any appropriate material, may be formed on or applied to the rounded flange 20, as shown in Fig. 7.

When the socket member is to be applied to the stud member, the head of the stud member is directed into the opening of the 80 socket member, and the two members pressed together, so that the resilient fingers 18 will engage with the rounded flange 20 of the stud member and yieldingly hold the two members together, as shown in Fig. 8.

It will be noted that the construction and arrangement of the parts of the socket member is such that there is little or no danger of injury to the parts during laundrying of the fabric to which the socket member is applied. The resilient fingers of the 85 spring member project into the interior of the socket member and are, therefore, well protected. Furthermore, as the resilient fingers are not held under tension, as is the case with the corresponding resilient means of former fasteners, there is no danger of their effectiveness being lost during laundrying. The stud member, as distinguished from frail bulbous-like stud members of 90 other snap fasteners, is sufficiently strong to withstand the treatment received during laundrying and will not be injured thereby. Both the socket and stud members project only a small distance from the fabric, 95 thereby lessening their liability to damage, and notwithstanding this fact, the parts are so constructed that both the socket and stud members are firmly and mechanically attached to the fabric. The neat and finished appearance presented by the socket and stud members of the improved fastener is apparent from Fig. 10.

Obviously numerous changes and modifications may be made in the details of construction, as above described, without departing from the spirit or scope of the invention, as defined in the accompanying claims.

What I claim is:—

1. A separable snap fastener for fabrics and the like, comprising stud and socket members, each having a tubular portion with substantially straight walls, and a thimble adapted to be expanded within the 100 130

same to attach the member to the fabric, and means whereby the stud and socket members may be separably connected.

2. A separable snap fastener for fabrics and the like, comprising stud and socket members each having a tubular part with substantially straight walls, means for mechanically attaching said tubular part to different portions of the fabric, and means whereby the stud and socket members may be separably connected.

3. In a snap fastener, a socket member, one element of which has a tubular shank, a thimble having its head portion only expanded within said shank to attach the socket member to a portion of the fabric, and a plurality of spring fingers associated with said thimble and extending a considerable distance into the interior of the expanded portion of the thimble, said spring fingers being rigidly backed at the entrance to the socket member by the unexpanded annular portion of the thimble.

4. In a snap fastener, a socket member, one element of which has a thimble-receiving chamber, a thimble having a basal flange-like portion and a head portion expanded within said thimble-receiving chamber of the socket member, and a disk-shaped

spring member associated with the flange-like portion of said thimble and having a plurality of spring fingers projecting a considerable distance into the interior of the expanded portion of the thimble, said fingers being rigidly backed at the entrance to the socket member by the unexpanded annular portion of the thimble.

5. In a snap fastener, a socket member, one element of which has a tubular shank with a basal inturned flange, a thimble having a basal flange-like portion and a head portion expanded in said shank behind said inturned flange, and a plurality of spring fingers associated with said thimble and projecting a considerable distance into the interior of the expanded portion of the thimble, said fingers being rigidly backed by the unexpanded annular portion of the thimble adjacent said inturned flange of the shank and at the entrance to the socket member.

In testimony whereof I affix my signature, in presence of two witnesses.

GEORGE C. SNYDER.
